UNITED STATES PATENT OFFICE

171,168

SANDWICH DISH

Lyall Mellor Ross, Balwyn, Victoria, Australia

Application March 17, 1953, Serial No. 24,066

Term of patent 14 years

(Cl. D44—15)

To all whom it may concern:

Be it known that I, Lyall Mellor Ross, a British subject, residing in Balwyn, in the State of Victoria, Commonwealth of Australia, have invented a new, original, and ornamental Design for a Sandwich Dish, of which the following is a specification, reference being had to the accompanying drawing, forming part thereof.

I claim:

The ornamental design for a sandwich dish, as shown.

LYALL MELLOR ROSS.
